COOLER

Filed Aug. 1, 1927

UNITED STATES PATENT OFFICE

ERNEST R. BURCHIEL, OF TACOMA, WASHINGTON

COOLER

Application filed August 1, 1927. Serial No. 209,972.

This invention relates to improvements in coolers or refrigerators, and particularly to that class of device in which the cooling is effected by the evaporation of water admitted to the walls of the cooling chamber. It is the principal object of this invention to provide a cooler of the above character having its walls molded from a novel composition of matter which is water accumulating to such an extent and which also so accelerates evaporation that it produces a construction that is more efficient than those heretofore used, which does not sweat or drip water internally or externally, and which is not subject to decay, mold or any deteriorating effect.

Another object of the invention resides in the provision of a basin in the top wall of the cooler in which water may be contained for absorption by the cooler walls.

Another object of the invention resides in the composition of material and method used in forming the walls of the cooler.

Other objects of the invention reside in the various details of construction and combination of parts as will hereinafter be described.

In accomplishing these and other objects of the invention, I have provided the improved details of construction, the preferred forms of which are illustrated in the accompanying drawings, wherein—

Figure 1 is a perspective view of a cooler constructed in accordance with the present invention.

Figure 2 is a partial vertical section of the same.

Figure 3 is a view, partly in plan and partly in horizontal section.

Figure 4 is a perspective detail of a part of the frame construction.

Referring more in detail to the drawings—

1 designates, in its entirety, a cooler or refrigerator embodied by the present invention. In its preferred form of construction, it is of the usual box-like form and comprises a wooden frame structure within which the cooler walls of composition material are molded in an integral body. The frame structure comprises the angular leg forming or corner pieces 2 at the four corners of the

box. The upper, lower and intermediate cross bars 3, 4 and 5, respectively, which are joined to the corner parts 2 in such manner as to provide a rigid and substantial frame structure, and the wooden casing 14 within which, as presently described, a door is fitted.

In manufacturing coolers of this character, the wooden frame structure is first assembled and then this is placed within a suitable mold within which the body of the cooler is cast, so that its walls are all integrally formed and the frame so embedded therein that the body and frame are permanently and rigidly joined.

The cooler body comprises the side walls 6, back wall 7, top wall 8 and bottom wall 9, all of which are cast in a single piece. The front of the body thus formed is left open and in this opening, which is defined by the casing 14, a door 10 is fitted. The door is bounded by a wooden frame structure 13 and is suspended from one side by hinges 11 and provided at its opposite edge with a latch 12. In Figures 1 and 2, the door is illustrated as comprising the wooden frame structure 13 in which is cast a central panel 15 of the same material as is used in making the body portions.

An important feature of the invention resides in the use of a composition of material from which the box may be cast and which will insure the results previously mentioned. This composition is prepared by mixing together ordinary fibre plaster, plaster of Paris, pumice stone and gypsum. Preferably, they are used in the following proportions:

	Per cent by weight
Fibre plaster	23
Plaster of Paris	47
Pumice stone	5
Gypsum	25

To this mixture a quantity of water sufficient to make it capable of being molded is added and the composition is then poured in the mold within the frame structure. It is desired also that reinforcing rods or wires 20, as shown in Figures 2 and 3, be secured with-

in the frame so that they will be embedded in the walls of the cooling chamber to give strength thereto and also which will more securely hold the frame structure and body together; the ends of the wires preferably being attached to screw eyes 21 fixed in the frame members as shown in Figure 4.

It has been found that a composition of this character will quickly absorb a large quantity of water and this will be discharged evenly to all parts of the body and will not drip or seep from or be visible on the walls. It also accelerates evaporation of the water to such an extent that the desired cooling is effected. In actual use the temperature within the cooler may be maintained at about fifty degrees Fahrenheit.

For the purpose of facilitating the application of water to the cooler walls, it is preferred to cast a shallow basin 25 in the top wall in which a quantity of water may be poured. This basin serves to retain the water until it has been absorbed by the walls and thus the undesirable results which would follow the pouring or splashing of water on the walls is avoided. It has been found that if the walls of the cooler are thoroughly saturated and a quantity of water remains in the basin, it will be retained there until sufficient moisture has been evaporated from the walls that this extra amount of water may be absorbed. At no time, regardless of the degree of saturation of the walls, will any water drip or sweat from the inside or outside surfaces.

Another important feature of the construction is that the door panel is insulated from the other parts by the wooden casing 14 and frame 13 and thus it does not absorb water from the walls. This provides, by virtue of the moisture absorbing property of the material, that any moisture arising from steaming food, viands or vegetables placed in the cooler will readily be taken up by the door panel and thus the undesirable results which might otherwise occur are avoided.

In order that the door panel will at all times be well insulated so as not to absorb water from the surrounding walls, the wooden frame which surrounds it is well treated with a water proofing material before it is placed in the structure. The other parts of the frame are also well treated with a water proofing material to prevent their warping due to absorption of moisture and to add to their durability. Also, all metal parts are treated with a rust proofing material to add to their durability.

Such cooling devices may be made in various sizes, shapes and proportions and may be equipped internally with suitable shelving, as has been indicated at 26 in Figure 2, so as to adapt them for various uses such as required in the ordinary home, in markets, hotels or on ships.

It is to be understood that while I have illustrated the cooler as cast within a wooden frame structure, it is not absolutely necessary that such be provided for the reason that it is possible to cast boxes of the material mentioned in various forms and shapes and without the frame structure, which will serve as well, in so far as the cooling effect is concerned, as if the frame structure were provided. However, the frame structure enhances the appearance of the device and also gives it strength and facilitates its being handled.

Having thus described my invention, what I claim as new therein and desire to secure by Letters Patent, is:

A cooler of the character described comprising a box-like cooling chamber having its walls integrally cast from a water absorbing material, and a basin formed in the top wall in which water may be contained for absorption by the walls and a door for the cooler having a wooden frame encasing it and whereby it is insulated from the body of the cooler, and a panel in said door of an absorbent material for taking up moisture from within the cooler.

Signed at Tacoma, Pierce County, Washington, this 21st day of June, 1927.
